UNITED STATES PATENT OFFICE.

SAMUEL B. CONNOR AND HENRY DODS, OF VIRGINIA CITY, NEVADA.

AUTOMATIC BALANCE ATTACHMENT FOR DELIVERY-VALVES OF AIR-COMPRESSORS AND WATER-PUMPS.

SPECIFICATION forming part of Letters Patent No. 232,939, dated October 5, 1880.

Application filed July 13, 1880. (No model.)

To all whom it may concern:

Be it known that we, SAMUEL B. CONNOR and HENRY DODS, of Virginia City, in the county of Storey and State of Nevada, have 5 invented a new and Improved Automatic Balance Attachment to Delivery-Valves of Air-Compressors and Water-Pumps, of which the following is a specification.

It is well known that in all air-compressors and water-pumps the pressure in cylinder of air-compressors or in working barrel or cylinder of pumps is much greater at the point of opening the delivery-valves than the actual pressure in air-receivers of compressors or water-column of pumps, because of the difference in area between the top and bottom of delivery-valves. In some air-compressors a hundred and twenty-five pounds pressure to the square inch is required in the cylinder to eighty pounds in 15 the receiver, and in some instances a hundred pounds pressure is required in the cylinder to eighty pounds pressure in the receiver or column.

The object of this invention is to remedy this 25 defect in air compressors and pumps, to provide a device whereby the compressors and pumps can operate with equal pressure on both sides of the delivery-valve.

The invention consists of an auxiliary valve 30 arranged outside of the cylinder, where it shall not be subjected to back-pressure, and connected with the delivery-valve by a hollow valve-stem.

The drawing represents a vertical sectional 35 elevation of the device.

In the drawing, A represents the cylinder 40 of an air-compressor in which there is a piston. (Not shown.) B is the ring on the end of the cylinder A, containing the delivery- 45 ports b b, through which the air from the cylinder A is forced into a receiver or conducting-pipes. (Not shown.) This ring B is provided with an inner flange or valve-seat, c, on which rests the delivery-valve C. D is the cylinder-head. These parts are similar to those seen in some of the air-compressors in common use, and with such construction and arrangement one hundred pounds pressure to the square inch in the cylinder A is required 50 to open the valve C against eighty pounds

pressure in the receiver or in the conducting-pipes.

By means of the standards E E we connect a drum, F, having an open end, to the cylinder-head D, and within this drum F we place 55 a valve, G, parallel with the valve C, and connect the two valves C G by means of a rod, H, that extends from the inner face of the valve C centrally through the cylinder-head D, and suitable stuffing-box and gland f g, respectively, and centrally through the bottom of the drum F and its stuffing-box and gland h i, respectively, into and through the valve G, and on the outer end of this rod H is screwed an adjusting-nut, I, by means of which 60 the valve G may be adjusted on its seat s, the bottom of the drum F. This rod H is provided with a longitudinal bore, m, that extends from its inner end, within the cylinder A, to a point on a level with the face of the valve-seat 65 s of the drum F, and at this point the said bore m is intersected by a lateral opening, n, that opens into the space between the valve G and its seat s.

It will be seen that the upper face of the 75 valve G is exposed so as to be subjected to atmospheric pressure only. Hence when the compressor is in operation a portion of the air in the cylinder A passes through the rod H into the space beneath the valve G, and 80 there exerts sufficient pressure, in combination with the pressure on the inner face of the valve C, to open said valve C against an equal pressure in the receiver or conducting-pipes. Hence when the pressure in the cylinder A 85 reaches the pressure-point in the receivers the valve C is opened and held in place until the piston in said cylinder A starts on the return stroke, when the pressure under the valve G is immediately exhausted through the rod H 90 and the main valve C closes.

The space between the valve G and its seat s should be as shallow as possible, that said space may be quickly filled and exhausted of air, and the valve G may be adjusted to regulate said space by being screwed on the rod H and held by nut I.

Having thus described our invention, we claim as new, and desire to secure by Letters Patent—

1. An automatic balance attachment to delivery-valves of air-compressors and water-pumps, constructed substantially as herein shown and described, consisting of the valve 5 G, within the drum F, connected with the delivery-valve C by the hollow rod H, as set forth.
2. The combination, with the delivery-valve C of an air-compressor or water-pump, of an auxiliary valve, G, connected therewith by a 10 hollow rod, H, substantially as herein shown

and described, the inner face of said auxiliary valve being subjected to the air or water pressure of the air-compressor or water-pump cylinder, while its outer face is subjected to atmospheric pressure only, as set forth.

SAMUEL BARTLETT CONNOR.
HENRY DODS.
